UNITED STATES PATENT OFFICE.

CHARLES HOFMANN, OF CHICAGO, ILLINOIS.

DESIGN FOR A CUSPIDOR-CASE.

SPECIFICATION forming part of Design No. 24,530, dated August 6, 1895.

Application filed June 21, 1895. Serial No. 553,607. Term of patent 14 years.

To all whom it may concern:

Be it known that I, CHARLES HOFMANN, a citizen of the United States, residing at No. 1230 West Fifteenth street, in the city of Chicago, in the county of Cook and State of Illinois, have invented and produced a new and original Design for a Cuspidor Case, Frame, or Inclosure, of which the following is a specification, reference being had to the accompanying drawing, showing the full front view of it.

The leading feature of my design consists in the figure of a clown B resting on a mattress A—the base of the design—in a half-reclined position, firmly holding with both his hands the rim of a paper hoop C, through the burst and tattered paper center of which appears the clown's head and neck bent forward, the neck adorned with a fluted ruffled collar of the Elizabethan fashion, his face complacently grinning on the supposed audience, with his mouth wide open, thereby display-

ing two rows of teeth, and the eyes sparkling in idiotic delight. The clown's legs are crossed, the right one bent under the knee in Turkish fashion and partly covered by the 25 left leg, that is thrust forward into the air, with the neatly-dressed foot D reaching out beyond the mattress-base. The circular-shaped hoop held by the clown's hands, with the clown's head and neck bursting through 30 it, forms the cover of the cuspidor, the whole design representing the complete figure of a clown reclining on a mattress, with his left leg outstretched and head and neck thrust through a paper hoop. 35

What I claim is—

The design for a cuspidor-case as herein shown and described.

CHARLES HOFMANN.
